SHEET METAL AND PIPE CUTTER

Frank Mart Hooley, Yuba City, Calif.

Application December 12, 1933, Serial No. 702,009

3 Claims. (Cl. 164—44)

This invention relates to sheet metal cutting implements; my principal object being to provide a simple implement for the purpose, adapted for use in sheet metal shops as well as by tinsmiths, by means of which sheet metal either in flat sheet form or in cylindrical or similar form, may be easily cut with a minimum of physical effort. A further object is to construct the device so that it may be easily mounted on an ordinary bench or the like and will occupy a minimum of space. The device is also of such an inexpensive nature that it is within the reach of any worker in the industry and is of so simple a character that there is nothing likely to give trouble at any time.

These objects I accomplish by means of such structure and relative arrangement of parts as will fully appear by a perusal of the following specification and claims.

In the drawing similar characters of reference indicate corresponding parts in the several views:

Figure 1 is a side elevation of the implement showing the blades in their lowered position and with the pipe slitter in its operating position.

Figure 2 is a sectional elevation of the implement showing the blades raised ready to make a cut.

Figure 3 is a similar view showing the cylinder cutting blade being removed.

Figure 4 is a cross section on the line 4—4 of Figure 1.

Figure 5 is a similar view on the line 5—5 of Figure 1.

Referring now more particularly to the characters of reference on the drawing, the frame of the implement comprises a pair of horizontal transversely spaced bars 1 and 2 having spacers 3 at their ends tied together by bolts 4 through the bars and spacers. The bars also have short spaced legs 5 provided with flat feet 6 extending therebetween, which are formed with slots 7 extending lengthwise of the frame and both open to the same end thereof. The slots serve to receive the upper ends of lag bolts 8 which are secured to a bench 9 on which the implement rests, the heads of the bolts bearing against the top of the feet. This method of mounting the frame enables the same to be easily withdrawn from engagement with the bolts so that it may be turned to occupy another position on the bench in connection with other bolts as operating conditions may require.

Mounted in the bars intermediate their end is a bolt 10, serving as a pivot blade 11 disposed between the bars and projecting toward one end of the same. The under edge of this blade is

the cutting edge thereof and it cooperates with the adjacent portion of the bar 1 which is bevelled as at 12 to form a stationary blade. The bolt engages a slot 13 cut in the hub 14 in the blade under the cutting edge and facing the outer end of the blade. The purpose of this arrangement will be seen later. The blade beyond the pivot is formed with a longitudinally extending cam portion 15 of substantially semi-elliptical shape.

Mounted in the bars beyond the blade 11 is another bolt 16 on which is permanently pivoted the hub 17 of a blade 18. This blade is provided at its outer end with a longitudinally extending but vertically offset handle 19 which extends beyond the corresponding end of the frame; the adjacent spacer 3 limiting the downward movement of the blade. The lower cutting edge of the blade also cooperates with the bar, the upper edge of which is bevelled as at 20 to form a stationary

blade. At its end facing the cam 15, the hub 17 is formed with a relatively long cam rib 21, normally projecting under the cam 15. The front surface of the hub 17 from its junction with the lip or extension 21 to the top of the hub, is concavely curved as at 22, making an angle of substantially 90° with the lip and adapted to engage the upper surface of the cam 15. The cam and what may be considered as the cooperating socket of the handle blade are so designed relative to each other and so positioned relative to the pivots of the blades that when the blades are horizontal, the under surface of the cam 15 and the lip 21 flatly engage each other, as shown in Figure 1, while the upper surface of the cam and the surface 22 diverge somewhat from each other, with the tip of the cam and the corner of the socket.

As the handle blade is raised the lip 21 moves down from the cam 15 and the surface 22 engages the upper surface of the cam. This exerts a downward pressure on said cam raising the blade 11. When the upper tip of the surface 22 engages the cam the blade 11 can be raised no further, since the tip of the cam is then engaged with the lip 21 and the surface of the latter from the point of engagement to its outer end causes the path of rotation of the tip of the cam, preventing further downward movement of said cam or upward movement of the blade. Also further upward movement of the handle blade is prevented by a removable stop pin 23 mounted in the bars 1 and 2 at the back of the hub 17 and engaging a stop 24 formed on the back end of the lip 21. With the downward cutting movement of the blade the contact of the cam and socket and the

relative movements thereof are of course reversed.

With this arrangement either blade may be used selectively since neither one interferes with the operation of the other. If at any time the blade 11 is not wanted the pin 23 is withdrawn, allowing further upward movement of the handle blade sufficient to disengage the cam from the lip 21. This enables said blade 11 to be raised to a vertical position so that it may be slid down and disengaged from the pin 10 as shown in Figure 3, when the implement is disengaged from the holding bolts 8.

In connection with this implement I mount an additional blade 25 on the bolt 10 outwardly of the bar 1, which projects beyond the adjacent end of the frame and is sharpened both along its outer edge and the adjacent lower edge portion. This blade is for the purpose of making an initial slit in a pipe etc. circumferentially thereof. This is done by resting the end of the blade diagonally against the end of the pipe and hitting down on said blade as indicated in Figure 1. This enables the pipe to be then supported across the frame of the implement with the end of the blade 11 entering the slit made by the starting blade as shown in Figure 2; the said blade 11 being pointed at its end to facilitate its entry into the slit.

When a pipe is being cut the frame of the implement is set at right angles to the bench on which said implement is mounted, the bolts 8 being disposed accordingly, so that the pipe will extend parallel to the wall back of the bench. When long strips are to be cut by the blade 18 the implement is shifted to a position parallel to the wall so that said wall does not interfere with the strips; another bolt being mounted on the bench in the necessary position to maintain the implement in such parallel relationship.

The blade 11, owing to its convexly curved cutting edge and to its shortness, may also be efficiently used for cutting out a circle in flat sheet metal. In this case of course the sheet metal is laid across the frame bars in front of the blade and turned and guided by hand against the blade as the latter is reciprocated back and forth by operating the handle.

From the foregoing description it will be readily seen that I have produced such a device as substantially fulfills the objects of the invention as set forth herein.

While this specification sets forth in detail the

present and preferred construction of the device, still in practice such deviations from such detail may be resorted to as do not form a departure from the spirit of the invention, as defined by the appended claims.

Having thus described my invention what I claim as new and useful and desire to secure by Letters Patent is:

1. A sheet metal cutter comprising a horizontal bar adapted to be mounted in a fixed position and with its upper edge forming a stationary blade, a movable blade having a longitudinal slot open to the outer end of the blade, a pin fixed in the bar and normally engaging the bottom of the slot to form a pivot for the blade, a handle member pivoted on the bar beyond the pin for swivel movement in a vertical plane, removable stop means limiting the movement of the handle in one direction, and cooperating disengageable elements on the pivot end of the handle and on the blade beyond the slot to operate said blade with a movement of the handle; said elements being arranged for disengagement from each other only when the stop means is removed to permit further turning of the handle whereby the blade may then be moved to withdraw the slot from about the pin. 15

2. A sheet metal cutter comprising a horizontal bar adapted to be mounted in a fixed position and with its upper edge forming a stationary blade, a movable blade pivoted on one side of said bar to cooperate with said edge, the blade being pointed, and a sharp ended starter blade to make an initial slit in a cylindrical member to be cut pivoted on the bar on the side opposite from the first named blade and adapted to be lowered when not in use to a level below the upper edge of the bar. 30

3. A cutting device comprising a horizontal member forming a fixed blade, a movable blade alongside and cooperating with said fixed blade, an operating handle longitudinally aligned with and beyond said movable blade, disengageable operating connections between the adjacent ends of the movable blade and handle to reciprocate the blade with the reciprocation of the handle and arranged for disengagement only when the handle is turned beyond a predetermined operative limit, and means including a non-removable pin mounting the movable blade on the bar for removal 45 therefrom only when the connections are disengaged. 40
